UNITED STATES PATENT OFFICE.

PETER AGUSTIN MCCARVILLE, OF CLARE, IOWA.

INTERMITTENT GRIP DEVICE.

SPECIFICATION forming part of Letters Patent No. 717,704, dated January 6, 1903.

Application filed March 21, 1902. Serial No. 99,365. (No model.)

To all whom it may concern:

Be it known that I, PETER AGUSTIN MCCARVILLE, a citizen of the United States, residing at Clare, in the county of Webster and State 5 of Iowa, have invented a new and useful Intermittent Grip Device, of which the following is a specification.

This invention relates to an intermittent grip device for the transmission of power, and 10 has for its object more particularly the production of a simple, cheap, and efficient means for utilizing a portion of the power of windmills and similar machinery to operate lighter machinery in addition to the machinery operated directly by the windmill or 15 other source of power.

The invention further consists in certain 20 novel features of the construction, all as hereinafter shown and described, and specifically pointed out in the claim.

The invention may be employed in connection with any source of power wherein a reciprocating beam or rod is employed, such 25 as the operative rods of windmills, to which it is more particularly applicable, and for the purpose of illustration I have shown it in the drawings thus applied.

Figure 1 represents a side elevation, foreshortened and partially in section, of a portion 30 of a pump and a portion of the operating-rod of a windmill with the improved apparatus connected therewith. Fig. 2 is a front view of the same.

The pump being driven is represented at 35 10 and the windmill driving-rod at 11, of the ordinary construction.

The improved apparatus which is the subject 40 of this invention consists of an endless belt, preferably in the form of a chain 12, disposed to operate over two sprocket-wheels 13 14, mounted on vertically-alined shafts 15 16, supported in a suitable framework 17, as shown. The wheel 13 will preferably be smaller than the wheel 14, the purpose to be 45 hereinafter described. The machinery to be driven will be connected to one of the shafts 15 or 16, and for the purpose of illustration a gear-wheel is shown at 18 to indicate the fact that the shaft 16 will be employed to transmit 50 the power. The device will generally be employed to run any light machinery—such as grindstones, churns, corn-shellers, and the

like—but may be employed to run any desired kind of machinery within its capacity.

Connected to the bar 11 at any convenient 55 point are two pawl-bars 19 20, preferably coupled together by a bracket 21, the latter having a vertical rod 22, passing through a hanger 23, attached, as by a bracket 24, to the rod 11, as shown. The rod 22 will be 60 surrounded by two coiled springs, one above and one below a transverse plate 27 in the hanger 23, so that the pawl-bars 19 and 20 will be yieldable during both their upward and downward movements, as hereinafter 65 shown.

Upon the lower end of the pawl-bar 19 is a hook or pawl 28, pointing upward and adapted to engage the chain 12 on one side when moving upward, and the pawl-bar 20 will be 70 likewise provided with a hook or pawl 29, pointing downward and adapted to engage the other side of the chain when moving downward. The pawl 28 will thus engage the chain when moving upward and pass over the 75 links without engaging them when moving downward, while the pawl 29 will engage the chain when moving downward and pass over the links without engaging them when moving upward. As before stated, the upper 80 sprocket-wheel 13 is smaller than the lower wheel 14, so that the two straight portions of the chain incline slightly inward, the object of this being to prevent the pawl-bars 19 and 20 from coming in contact with the chain during 85 their movement. By this arrangement when the pump-rod 11 or other reciprocating source of power is reciprocated vertically the pawl-bars 19 and 20 will reciprocate with it and constantly revolve the chain both during 90 the upward and downward stroke, as will be readily understood. By this simple means the reciprocatory movement of the rod 11 is transmitted to the shaft 16 and thence to the machinery which it is designed to operate. 95

The springs 25 and 26 perform an important function, as they provide a yieldable joint or coupling between the rod 11 and the levers 19 and 20, so that all sudden jars or shocks are absorbed and the strains thereby 100 greatly lessened, while at the same time eliminating the noise or rattling to a large extent.

The parts may be constructed of any size or of any quality of material to adapt them

to the work required of them and to adapt the apparatus to the machinery to be operated and may also be modified and changed in minor particulars without departing from the spirit or scope of the invention.

Having thus fully described my invention, what I claim as new, and desire to secure by Letters Patent, is—

In a device of the class specified, the combination with a pair of sprocket-wheels of different diameter, of a link belt passing over said sprocket-wheels, a reciprocating rod, a bracket carried thereby, a spring-support carried by said bracket and having a guiding-opening, a rod adapted to said guiding-opening, springs encircling said rod on either side

of the support and forming an elastic connection between the rod and support in both directions of movement, a cross-bar or bracket secured to the rod, a pair of depending pawl-bars secured to said cross-bar or bracket, and oppositely-facing pawls rigidly secured to the pawl-bars and adapted respectively to engage opposite leads of the link belt, substantially as specified. 20

In testimony that I claim the foregoing as my own I have hereto affixed my signature in the presence of two witnesses.

PETER AGUSTIN McCARVILLE. 25
